UNITED STATES PATENT OFFICE.

CHARLES NELSON, OF BROOKLYN, NEW YORK, ASSIGNOR TO S. STERNAU & CO., OF NEW YORK, N. Y., A COPARTNERSHIP COMPOSED OF SIGMUND STERNAU AND LIONEL STRASSBURGER.

COFFEE-MACHINE.

1,111,083.

Specification of Letters Patent. Patented Sept. 22, 1914.

Application filed April 24, 1907. Serial No. 369,923.

To all whom it may concern:

Be it known that I, CHARLES NELSON, a subject of the King of Sweden, residing in the borough of Brooklyn, county of Kings, 5 and State of New York, have invented an Improvement in Coffee-Machines, (Case C,) of which the following is a specification.

This invention relates to an improvement in a machine for making infusions of coffee, 10 tea and similar beverages. The invention is not limited to such use as it may be employed in connection with machines for other and analogous purposes.

The objects of the invention are to produce a device which has no moving parts, 15 which is simple, cheap to construct, will not get out of order, and which may be readily and thoroughly cleaned.

Another object is to produce a device 20 which will operate in the minimum of time and exposure to heat, and by means of which an infusion may be induced without bringing all of the water in the receptacle to a boil.

25 These and other objects will appear from the following drawings in which—

Figure 1 is a sectional view of a portion of a coffee machine embodying my invention. Fig. 2 is a side elevation of the lower end 30 of the percolator. Fig. 3 is a sectional view thereof. Fig. 4 is a sectional view on the line *a—a* of Fig. 3.

In all of the several views like parts are 35 designated by the same reference characters.

In carrying out my invention I provide a receptacle 1 for water or other liquid, with a screen 2, which latter is carried by the globe 3. The percolator shown generally at 40 4 extends up through the sieve or screen 2 and ends below the deflector 5. The percolator drives the liquid up against the deflector, which sprays and splatters it over the material which lies within the screen 2, thereby reducing the infusion, which sinks 45 back into the receptacle 1.

The percolator 4 rests within a chamber 6, which chamber is attached to the bottom of the receptacle 1 and communicates with the latter. A plate 7 may be attached to 50 the bottom of the chamber for the purpose of concentrating the heat in the spirit lamp or other source of heat employed and for preventing the flame coming into contact with the bottom of the receptacle. The percolator comprises a tube 8, which is vertical 55

and open at each end, the lower end extending down into the chamber 6. Surrounding the lower part of the tube 8 is an air chamber 9. This air chamber is shown in Fig. 3 as being formed of an upper bell-shaped piece 10 and a lower corrugated piece 11. The lower end of the tube 8 enlarges slightly and snugly fits within the lower corrugated piece throughout the greater portion of the length of the latter. The lower end of the lower piece and the upper end of the upper piece are soldered with a tight joint to the tube 8 so that the liquid cannot enter the air chamber 9. As shown in Fig. 4, the lower corrugated piece 60 11 is elliptical in cross-section, its longer diameter being substantially equivalent to the diameter of the chamber 6, such chamber being cylindrical in shape. The shorter diameter of the piece 11 is less than the diameter of the chamber whereby passages 65 12—12 are produced on each side of the chamber between the inner wall thereof and the lower corrugated piece 11.

The operation is as follows: In making 70 coffee, the receptacle 1 is partly filled with water, and the coffee is placed within the screen 2. The water will enter the chamber 6 through the passages 12, and will rise in the tube 8 to the height of the level of the water within the receptacle 1, or slightly higher, as depends upon the effect of capillary attraction. Heat is now applied to the bottom of the chamber 6 and plate 7 by any suitable means, as for instance, by means of 75 a spirit lamp. In a very few moments the contents of the chamber 6 will be heated, expanding the liquid within the tube 8 and generating steam in the chamber 6. The tube 8 and the chamber 6 are sufficiently 80 small to prevent any considerable circulation of water from the lower end of the chamber 6 to the upper portion of the tube 8. The water in the lower part of the chamber 6 will very soon begin to boil, and the pressure of steam will force the liquid up 85 the tube 8 against the deflector 5, where it will be sprayed and splattered over the coffee in the screen 2, and will seep through the coffee and back into the receptacle. As 90 soon as the pressure is released within the tube 8 by the liquid being driven out thereof at the top, the level within the tube will be restored by cold water entering the chamber 6 through the passages 12. This 95

100 105 110

again will become heated and the operation will be repeated, and so on, until an infusion of the desired strength is produced. Ordinarily this can be secured before the 5 contents in the receptacle 1 has been brought to a boil, thus avoiding the injurious effects to the coffee by boiling it. The liquid will pass out in the tube 8 more readily than out of the passage 12, as the tube 8 is straight 10 and of considerably larger cross-section than the passages 12; furthermore, one wall of each passage 12 is made up of corrugations of the piece 11. These corrugations act, to some extent, as baffling grooves and prevent 15 the free passage of the liquid from the chamber 6 when it is driven out by the formation of steam in the latter. This formation of steam is very sudden, and the liquid is driven out of the chamber 6 with considerable 20 velocity; hence the greater portion will pass up the unobstructed tube 8 and not through the passages 12. The passages 12, however, permit the liquid to enter the chamber 6 from the receptacle 1.

25 The air chamber 9 serves the useful purpose of preventing the liquid within the lower part of the receptacle 1 from becoming heated by convection from the chamber 6. The plate 7 not only concentrates the 30 heat to the base of the chamber 6 but prevents the heat of the lamp from reaching the bottom of receptacle 1; therefore, by means of the plate 7 and the air chamber 9 the liquid in the bottom of the receptacle 35 1 is not heated. I find that without the chamber, or its equivalent, the effects of the device are greatly inferior, and that the time required to secure the operation is much longer.

40 The broad feature of the invention comprising a labyrinthine passage from the heating chamber to the receptacle is not claimed herein, but forms the subject matter of a pending application.

45 In accordance with the provisions of the patent statutes, I have described the principle of my invention, together with the ap-

paratus which I now consider to represent the best embodiment thereof; but I desire to have it understood that the apparatus 50 shown is merely illustrative and that the invention can be carried out in other ways.

Having now particularly described the nature of my invention, and in what manner the same is to be performed, what I 55 claim and desire to secure by Letters Patent is:

1. A percolator for coffee machines having a central open-ended tube and a horizontally corrugated member adjacent to one end of the tube and surrounding the same, in combination with a heating chamber surrounding the corrugated member. 60

2. A percolator for coffee machines having a central open-ended tube, a horizontally corrugated member adjacent to one end of the tube, and surrounding the same and a chamber above the corrugated portion, in combination with a heating chamber surrounding the corrugated portion. 65

3. The combination of a receptacle with an open-ended heating chamber, a percolator, the said percolator having a horizontally corrugated member surrounding its 70 lower end and extending into the chamber.

4. The combination of a receptacle with an open-ended heating chamber of circular cross-section, a percolator, the said percolator having a member of elliptical cross-section extending into the chamber providing 75 passages between the walls of such member and chamber. 80

5. The combination of a receptacle with an open-ended heating chamber of circular cross-section, a percolator, the said percolator having a corrugated member of elliptical cross-section surrounding its lower end and extending into the chamber. 85

This specification signed and witnessed this 22nd day of April, 1907.

CHARLES NELSON.
